(57) **CLAIM**

The ornamental design for an electric vehicle charger as shown and described.

DESCRIPTION

FIG. 1 is a front view of an electric vehicle charger, showing the new design;

FIG. 2 is a right side view of the electric vehicle charger of FIG. 1;

FIG. 3 is a back view of the electric vehicle charger of FIG. 1;

FIG. 4 is a left side view of the electric vehicle charger of FIG. 1;

FIG. 5 is a top, front, right perspective view of the electric vehicle charger of FIG. 1;

FIG. 6 is a bottom, front, right perspective view of the electric vehicle charger of FIG. 1;

FIG. 7 is a bottom view of the electric vehicle charger of FIG. 1; and,

FIG. 8 is a top view of the electric vehicle charger of FIG. 1.

The ornamental design which is claimed is shown in solid lines in the drawings.

The broken lines of equal length dashes in the drawings depict portion of the article that form no part of the claimed design.

1 Claim, 8 Drawing Sheets
